UNITED STATES PATENT OFFICE.

MERVIN B. CANNON, OF CINCINNATI, OHIO.

PACKAGING MACHINE.

Application filed April 2, 1920. Serial No. 370,775.

To all whom it may concern:

Be it known that I, MERVIN B. CANNON, a citizen of the United States, residing at Cincinnati, in the county of Hamilton and 5 State of Ohio, have invented certain new and useful Improvements in Packaging Machines, of which the following is a specification.

My invention relates to machines for making special packages; and the objects of my invention are to combine in a single package a plurality of objects, one of which forms the wrapper of the package, and preferably to make the package very compact and smooth, so as to be readily dispensed in a suitable vending machine. Other objects will appear in the course of the ensuing description.

I attain these objects by the mechanism illustrated, for example, in the accompanying drawings, in which—

Figure 1 is a side elevation, with parts in vertical lengthwise section, of a machine embodying my invention;

25 Fig. 2 is a vertical cross-section of the forming-box on a plane corresponding to the line 2—2 of Fig. 1;

Fig. 3 is a partial plan view of this machine, up to and including the folding-table;

30 Fig. 4 is a sectional side elevation of the same, similar to Fig. 1;

Fig. 5 is a plan view of the cutting mechanism and folding-table; enlarged;

Fig. 6 is a sectional side elevation of the 35 same;

Fig. 7 is a partial side elevation of the middle parts of the machine including the initial-rolling mechanism;

40 Fig. 8 is a perspective view of a fragment of the web with its first creases;

Fig. 9 is a similar view of the same with its first folds;

Fig. 10 is a similar view of the same with the beginning of the second fold;

45 Fig. 11 is a similar view of an individual piece cut off from the finally-folded and flattened web;

Fig. 12 is a detail front elevation of the folding-arm shifting-lever;

50 Fig. 13 is a detail side elevation of the same together with its support and driving cam and folding-arm connection;

Fig. 14 is a plan-view of the folding and soap-inserting mechanisms;

55 Fig. 15 is a delivery-end elevation of the soap-inserting mechanism;

Fig. 16 is a vertical lengthwise section of the same, on a plane corresponding to the line 16—16 of Fig. 14;

Fig. 17 is a perspective view of the piece 60 of sheet material with its transverse fold being formed;

Fig. 18 is a similar view of the piece with this fold completed;

Fig. 19 is a similar view of the initially-65 rolled package;

Fig. 20 is a cross-sectional delivery-end elevation of the transverse-folding mechanism;

Fig. 21 is a similar view showing a modification of the cam details, and with the shifting-lever and folding-arm and bar in their withdrawn positions;

Fig. 22 is a feed-end elevation of the modified cam;

Fig. 23 is a front elevation of the same;

Fig. 24 is a perspective view of the rolled package;

Fig. 25 is a front elevation of the clip-table;

Fig. 26 is a cross-section of the same, on a vertical plane corresponding to the line 26—26 of Fig. 25;

Fig. 27 is a similar view showing a modification;

Fig. 28 is a detail front elevation of the initial-rolling driving mechanism;

Fig. 29 is a perspective view of the completed package;

Fig. 30 is a plan view of the rolling and 90 binding mechanisms;

Fig. 31 is a detail plan view of the tape-guiding and flattening rolls;

Fig. 32 is a partial vertical cross-section on a plane corresponding to the line 32—32 95 of Fig. 30, showing the lower tape guides, and the construction of the cutting and moistening rolls, and also showing adjacent parts of the rolling belts by dotted lines;

Fig. 33 is a delivery-end elevation of the 100 machine;

Fig. 34 is a detail delivery-end elevation of the tape-cutting roll, partially in longitudinal section; and

Fig. 35 is a similar view of the tape-105 moistening roll;

Fig. 36 is a side elevation of the rolling and binding mechanisms.

In practice, I prefer, for the particular purpose of my invention as herein exemplified, to wrap together two pieces of towel material, preferably crêpe-paper of a weight

suitable for the purpose, and a single small piece of soap, binding them with a piece of adhesive tape, making a package similar to that disclosed and claimed in my Patent No. 5 1,346,441, dated July 13, 1920, and preferably forming this package in a very firm, compact condition with suitable symmetry and smoothness to be readily dispensed automatically in a vending machine.

- 10 10 While two or more thickness of the paper or other sheet material may be wrapped together, I have, for sake of simplicity, treated the plurality of sheets as a single sheet, in the illustrations and description herein.
- 15 15 For supplying the sheet material in web form, a suitable reel or the like is provided; and just before entering the machine the webs or web may pass through suitable means for printing or otherwise marking thereon or therein any display matter, advertising or other kind, which it may be desirable to have appear thereon. Also, suitable guiding and supporting means, such as idler rollers, may receive the webs or web 20 20 before entering the machine, to facilitate renewal of the supply without stopping the machine. Such apparatus as any of these are well known, and require no illustration or detailed description herein.
- 25 25 The machine comprises the pedestal 1 of box-like formation, extending from the left or feed end for the major part of the length of the machine. The first-creasing roll standards 2 are supported on this pedestal 30 30 1 at opposite sides thereof, near the left end. Each standard 2 has upright guides 3 near its top, with the lower creasing roll 4 journaled between their bottoms, preferably in ball-bearings 5. In each pair of guides is 35 35 the bearing block 6, in which blocks is journaled the top first-creasing roll 7, against the lower roll 4. A helical spring 8 is compressed between the top of each bearing block 6 and a bar 9 also guided in the respective guides 3 and held down by an adjusting screw 10 in a cap 11 bolted to the guide tops. The upper and lower rolls 7 and 4 have spur gears 12 and 13, respectively, concentrically 40 40 fixed on them and meshing together; and the upper roll 7 also has similarly fixed to it, outside the front standard 2, a sprocket wheel 14. A driving shaft 15 is journaled transversely in the pedestal 2 below the standards 2, with a sprocket wheel 16 fixed 45 45 50 50 55 55 on it at the front; and a sprocket chain 17 passes around the wheels 14 and 17.
- 60 60 The upper roll 7 has annular flanges 18 at its ends, and the lower roll has end offsets 19 receiving the flanges 18. Also, the upper roll 7 has, spaced substantially equally from each other and from the flanges 18, annular ridges 20; and has adjacent to the middle ridge 20, at each side thereof, a depression 20^a, entirely around the roll and extending 65 65 65 a considerable distance toward the end of

the roll (Fig. 3). The lower roll 4 has annular grooves 21 receiving the upper roll ridges 20; and the depressions 20^a leave empty spaces between the rolls, allowing the sheet material to stretch the required degree to 70 form the middle crease under the action of the cooperating middle groove 21 and middle ridge 20, as is readily possible with such materials as towels and the like are made of. Crêpe tissue is especially susceptible to this 75 on account of its wrinkly condition.

A proper distance to the right of the just described mechanism is another pair of standards 22, transversely spaced, and a shorter standard 23 between the standards 22, at the middle of the pedestal 1. A yoke 24 is fixed across on the tops of the standards 22, with an arm 25 depending from its middle. A stud 26 projects to the right from the lower end part of this arm, and on this stud are four arms 27 projecting diagonally upward and downward with equal spacing around the stud 26, forming a spider which supports the surrounding hollow core 28, of a cross-section which is rectangular, with substantially equal sides, at the left or feed end, and with its sides running diagonally so that two of its corners are in vertical and the other two of its corners are in horizontal alignment. This cross-section continues for 80 80 85 85 90 90 95 95 100 100 105 105 110 110 115 115 120 120 125 125 130 130 a very short distance, then merging into one that gradually changes to a very much flattened and correspondingly widened quadrangle. Surrounding this core, with its interior sides spaced sufficiently from corresponding sides of the core, are the two sections of the shaping-box, the rear section 29 having at its top two shackles 30 hinged to drop into forks 31 at the top of the front section 32, and both sections being concentrically hinged on an axis lengthwise of the machine, constituted by a pin 33 with its feed-end supported by the middle shorter standard 23 and a similar standard 34 at the delivery-end thereof. These box-sections 110 110 115 115 120 120 125 125 130 130 135 135 140 140 145 145 150 150 155 155 160 160 165 165 170 170 175 175 180 180 185 185 190 190 195 195 200 200 205 205 210 210 215 215 220 220 225 225 230 230 235 235 240 240 245 245 250 250 255 255 260 260 265 265 270 270 275 275 280 280 285 285 290 290 295 295 300 300 305 305 310 310 315 315 320 320 325 325 330 330 335 335 340 340 345 - wheel on the upper roll shaft; this latter having a chain around it, which chain passes around the driving sprocket wheel on a shaft transversely journaled in the pedestal below the standards. All of these parts being like those of the first set of rolls, they are correspondingly numbered. But this second set of rolls are not so wide as the first set. The lower roll 36 has the 10 offsets 19' in its ends and the upper roll 37 has the flanges 18' on its ends, entering the offsets, the same as the first rolls. The upper roll 37 has a single annular ridge 20' around its middle, entering a single 15 annular groove 21' around the middle of the lower roll 36. The coaction and adjustability of these rolls 36 and 37, having the same mounting and driving means, are like those of the first rolls 4 and 7.
- 20 A proper distance to the right of the roll mechanism just described is a bench 38 crosswise of the pedestal 1 with uprights 39 at its ends at front and rear of the machine, with a top-piece 40 fixed across on the 25 tops of these uprights. At the rear is the rear final flattening roll 41, journaled, on a vertical axis, in the top of the bench 38 below and the top-piece 40 above, preferably in ball-bearings 42 therein. The front final 30 flattening roll 43 is journaled in blocks 44 slideable from front to rear in guides formed at the sides of suitable openings in the bench-top and top-piece, respectively; these blocks being pressed rearwardly by helical 35 springs 45 compressed between the blocks and screw-plugs 46 in the bench-top and top-piece at the front. The rear roll 41 has offsets 47 and the front roll has flanges 48 entering the offsets 47, at the upper and 40 lower ends of the rolls. These rolls have no ridges nor grooves around them.
- A proper distance to the right of this mechanism just described is a frame made up of sides 49 standing upright at front 45 and rear of the pedestal 1. The left-hand or feed-end parts of these sides are similar to the standards 2 of the first-creasing and second-creasing mechanisms before described; and the mountings and driving elements 50 of the cutter-feeding rolls 50 and 51 in these frame-sides 49 are the same as in those mechanisms. These parts are therefore correspondingly numbered, as are also the sprocket chain and its wheel fixed on the transverse shaft in the pedestal 1 below this frame, for driving this cutter-feeding 55 mechanism.
- The frame sides 49, in their parts to the right of the standards, are not so high as 60 the standards, and at their right-hand ends, on their tops, they have the cutter-rotor 52 journaled in them, preferably in ball-bearings 53, which rotor has, outside its rear bearing, a spur gear 54 fixed concentrically 65 to it. Below and to the left of the rotor,
- two idler gears 55 and 56 are journaled on studs projecting from the rear of the frame, the upper one, 55, meshing with the rotor gear 54 above and with the lower idler gear 56 below, and this lower gear 56 meshing 70 with the gear 18' of the lower cutter-feeding roll 50. The cutter-rotor 52 has a projection 52' with one side flat and the other receding down to the normal convex surface of the rotor; and on the flat side is mounted 75 the blade 57 by means of clamp-screws 58 through slots 58' in the blade and screwed into the projection 52'. These slots, running back from the cutting edge, permit the blade to be adjusted inwardly or outwardly 80 substantially radially of the rotor. To permit this adjustment to be nicely made, adjusting screws 59 are threaded approximately diametrically through the rotor against the back of the blade. To cooperate with the rotor blade 57 a fixed blade 60 is mounted on a cross-bar 61 by means of clamp-screws 62 through slots 63 in the blade and screwed into the cross-bar. These slots, running back 85 from the cutting edge, permit the fixed blade 60 to be adjusted toward or from the rotor blade 57. This adjustment is made with keys 64 fitting between the blade 60 and inclines 65 on the cross-bar 61 and pushed in from the front and rear sides, respectively, 90 by adjusting screws 66 threaded through small brackets 67 screwed to lugs on the tops of the frame. The rotor and fixed blade are positioned at such a height that the upper surface of the fixed blade, located 100 between the rotor 52 and the cutter-feeding rolls 50 and 51, is slightly below a horizontal tangent to the meeting rolls 50 and 51.
- Preferably, all of the rolls 7, 4, 36, 37, 41, 43, 50 and 51 are suitably scored, striated or roughened, to permit them to properly grip and feed the web between the rolls of the respective pairs.
- The folding-table 68 extends from under 110 the cutter-rotor 52 past the delivery end of the pedestal 1; being formed of two parts 68' and 68'' bolted to a back plate 69 mounted on the pedestal top at the rear. The top of this table 68, in both parts 68' and 68'', is flat, and set a substantial distance down from the bottom of the cutter-rotor 52; while the adjacent ends of the two parts 68' and 68'' are, respectively, concave and convex on concentric curves, the center of 115 which is the axis of a bearing in a bracket 70 fixed on a delivery-end extension of the folding-table. These concentric ends of the parts 68' and 68'' are spaced slightly more than the thickness of the folding-bar 71, fixed in the free end part of the folding-arm 120 72 which has its hub 73 at the other end, with a square opening through which extends the folding-shaft 74, journaled at the rear in the mentioned bracket 70 and at the front 125 in a post 75 some distance forward from the 130

front of the folding-table 68 and mounted on a base plate 1' on which the entire machine, including the pedestal 1, is mounted. To the rear of the bracket 70 a short arm 76 is fixed on the folding-shaft 74, extending up at a proper angle from the folding-arm 72, and having pivoted to its free end a link 77 that extends toward the feed-end and is pivoted to a rocker 78 fulcrumed in a bracket 10 to the rear of the folding-table 68. This rocker 78 is of a width from front to rear to bring another link 79 pivoted to it coaxially with the pivoting of the link 77, back of a slotted lever 80 fulcrumed below in a bracket 15 to the rear of the folding-table vertically under the axis of the cutter-rotor 52, to the upper end part of which lever the link 79 is pivoted. A wrist 81 is fixed in the cutter-rotor gear 54 and extends back through the slot 82 in the lever 80. This slot has its middle part arcuate so that, during the cutting period of the cutter-rotor rotation, no motion is imparted to the lever 80; but the upper and lower end parts of this slot receive the wrist with a bearing fit, so that the remainder of the rotation of the rotor oscillates the lever 80 through equal angles from the vertical. The wrist is so positioned in the gear 54 that this oscillation is toward 30 the delivery end during the half of this remainder prior to cutting, and in the opposite direction during the other half, after the cutting. Thus the folding-arm and bar 71 are raised above the top of the folding-table 35 68 prior to cutting, and then, just after the cutting, start down along the arc-shaped slot between the folding-table parts 68' and 68'', stopping after the folding-bar 71 has passed from under the folding-table upper 40 part 68'' at the delivery end of the slot. During this downward sweep of the folding-arm and bar 71, the folding-arm 72 is at the inner end of the travel it has on the square part of the folding-shaft 74, to carry the 45 folding-bar 71 in the arc-shaped slot as just described. The folding-bar 71 is preferably of wedge-shaped cross-section, with the narrow edge downward. This edge is rounded and smooth, to avoid cutting of the material 50 folded thereby.

Another shorter post 83 is mounted on the base-plate 1' shortly to the rear of the post 75, and a cam 84 is journaled in these posts 75 and 83. This cam 84 is cylindrical as 55 shown, except in Figs. 21, 22 and 23, where a face-cam is shown, either form being suitable. Either cam has its slot or face, as the case may be, so shaped that the lever 85, having trunnions 85' with rollers in the cam slot, or, as in Fig. 21, the roller-finger of the lever 85'' on the cam face, is held stationary and inclined over toward the folding-table 68 (Fig. 20) or approximately vertical, away 60 from the folding-table, as shown by dotted lines in Fig. 20 or the full lines in Fig. 21;

and so the lever is shifted from one of these positions to the other. With the face cam of Fig. 21, the lever 85'' is pulled away from the folding-table 68 by the spring 84' attached to the lever and to the post 75. 70 The fulcrum of the lever 85 or 85'' is in two arms 86 fixed to opposite sides of the post 83 below the cam bearing and bent out around the cam and then inward, flanking the lever at the fulcrum. The upper end of 75 either lever has a fork flanking the hub 73 of the folding-arm 72, which hub has an annular groove containing a collar 87 with trunnions entering slots in the fork members. The just described cam slot or face has its 80 parts so positioned that when the cam is rotated by a sprocket chain 88 around its sprocket wheel 89 in front of the post 75, the folding-bar 71 is withdrawn forwardly entirely from the folding-table 68 during the 85 upward swing of the arm, but is shifted backwardly over the table just before it starts to swing downward along the slot between the folding-table parts 68' and 68'' as before described. 90

At the entrance to the curved slot, in the folding-table top, are rollers 90, at opposite sides of the slot, extending across the table from front to rear. Also, preferably, this folding-table 68 has (Fig. 5) a ledge 91 projecting up throughout its length along its rear side; and front ledges 91' and 91'' running to the left and right ends, respectively, from the curved slot on the front side. 95

Mounted on the folding-table part 68'' 100 above the exit of the curved slot, is a bracket 92 with arms 93 pivoted on its opposite sides, at front and rear, which arms have a roller 94 journaled in their free ends and are yieldably held down by springs 95 coiled around the pivot pin of the arms with their opposite ends engaging the bracket back and the arm upper edges, respectively. This roller 94 is thus yieldably held down. The clip-table 96 extends under the folding-table lower part 68' and its upper surface curves down from and is concentric with the curve of that part. 110

This clip-table 96 extends from the end of the lower folding-table part 68' some 115 distance toward the delivery end of the machine. It has a longitudinal slot 97 in its middle; and near opposite ends, in its sides, has suitable bearings 98 on which are journaled sprocket-wheels 99, with a sprocket chain 100 around them under the slot 97. At each end of the slot 97 is a wide recess 101 through the clip-table top. At equal intervals along the chain 100 are the lower clip-jaws 102 straddling and fixed to a link of the chain, and the upper clip-jaws 103 straddling these and pivoted on an elongated pin 104 in one of the link junctions. Both lower and upper jaws 102 and 103 are 125 extended laterally to front and rear of the 130

machine, and make mutual contact in planes parallel, with the horizontal plane of their chain-upper-stretch travel, during which they pass very close to the clip-table top. 5 They pass above this top through the recess 101 and the slot 97 affords passage for their supporting parts reaching down to their attachment to the chain 100. A spring 105 is of U-shape, with its legs coiled around 10 opposite end parts of the pin 104' of the adjacent link and its transverse part engaging the back of the upper-jaw supporting part; thus yieldably holding this upper, 15 jaw 103 in the aforesaid contact with the lower jaw 102. Cam-plates 106 flank the sprocket wheels 99 and fit around the sprocket-wheel shafts, each with an eccentric sector 106' at its feed end dropping abruptly to a straight top, which top has near its 20 delivery end an upwardly inclined abruptly dropping extension 106''; and each upper-jaw supporting part has an extension 107 that rides up on the sector 106' while the jaws are coming up through the recess 101, 25 opening the jaws to receive the folding-bar 71 and rides upon the extension 106'' just before passing down from the table top near the other end of the table, again opening the jaws. Thus the jaws are left closed 30 under the action of the springs 105 during their travel along the top of the clip-table 96. The two pairs of jaws go through these operations alternately, as carried around by the chain 100, which is driven by means 35 of a spur-gear 108 fixed on the shaft of the delivery-end sprocket wheel 99, meshing with a spur-gear 109 turning with a sprocket wheel 110 having a sprocket-chain 111 around it and around a sprocket wheel 112, 40 driven as hereinafter described. These latter wheels will be understood to be suitably journaled in frame-work mounted on the bed-plate 1' below the clip-table 96.

In Fig. 27, the modified jaw extension 107^a 45 engages the hardened knife-edged pieces 106', fixed to the clip-table 96^a, at respective ends of the table; those at one end only being shown. This affords less gradual openings of the jaws, as may be desired 50 under some conditions.

Back of the clip-table 96 is a frame 113 with a cam-shaft 114 journaled transversely in it, and a crank-shaft 115 similarly journaled in it lower down and nearer the 55 feed end of the machine. The cam-shaft 114 is driven by means of a sprocket wheel 116 with a sprocket-chain 117 around it and around another sprocket wheel 118 turning with the sprocket wheel 112; and this cam shaft 114 has a spur-gear 119 fixed on it and meshing with a spur-gear 120 of half its diameter, fixed on the crank-shaft 115. A harp 121 straddles the cam 122, being pivoted on the cam shaft 114 to swing lengthwise of the machine, and has its lower end 60 pivoted to a yoke bar 123 extending between the crank-disks 124 in the crank-shaft 115, with its yoke 125 around the crank wrist 126, and extending to the left through a guiding swivel-block 127 on the frame 113. 70 The initial-rolling shaft 128 is mounted to slide endwise and to rotate in bearing members 129 which are mounted to slide up and down in the slotted upper end parts of the harp 121, being yieldably held down by upper springs 130. The longitudinal sliding is effected by the inserting-arm 131, having forks at both ends, the upper one straddling a hub 132 fixed on the initial-rolling shaft 128 with a collar 133 journaled around it 75 having trunnions 134 engaging in lengthwise slots of the fork-members (Fig. 15,) and the lower fork of this inserting-arm 131 straddling the cam 122, with trunnions entering the cam-slot and being fulcrumed on the bottom of the harp 121 just below the cam, by the cross-shaft 135. At the front and rear of the top of the frame 113 are rails 136 and 137, respectively, lengthwise of the machine, and the initial-rolling-shaft 80 bearing members 129 have roller members 138 and 139, respectively, rolling on these rails, under the pressure of the springs 130. Just in front of the front rail 136 is the rack-guide 140, with rollers 141, on which a 85 rack 142 may travel lengthwise parallel with the rails. A pinion 143 has a square bearing on the square part 144 of the initial-rolling shaft 128 and is held to the bearing member 129 so as to rotate the shaft 128 but 90 to allow this shaft to slide lengthwise; this pinion 143 meshing with the rack 142. A bell-crank with its upper member 145 having a slot receiving a pin 146 fixed in the rack 142, and with its lower member pivoted 95 to the yoke-bar 147, is fulcrumed on a stud 148 projecting from the front side of the frame 113. The yoke-bar 147 has its yoke 149 around another crank-wrist 150 which is 100 coaxial with the crank-wrist 126 on the crank-shaft 115, but spaced therearound ninety degrees from the wrist 126 (Fig. 28). This yoke-bar 147 has the guiding swivel-block 151 on the frame 113 below the crank-shaft 115. The slot of the cam 122 has 105 diametrically opposed inclines with intervening uninclined parts, causing the inserting-arm 131 to swing forward or backward during respective minor portions of cam rotation, and to dwell at respective ends of its 110 swing during the remaining portions. The crank 126 is so geared to this cam 122 that it swings the harp 121 one way or the other during a respective dwell of the inserting-arm 131; and the crank-wrist passes the center while the inserting-arm 131 swings forward or backward, thus imparting practically no swinging to the harp 121 during this swinging. The other crank 150 pulls 115 the rack 142 toward the feed-end of the ma- 120

65 125

70 130

chine as the harp 121 swings toward the delivery end, and pushes the rack in the opposite direction as the harp swings back. The slot of the yoke 149 has an offset 152 occupied by the wrist 126 in an early sector of its over travel, leaving the rack 142 stationary for some time at the delivery-end of its stroke.

Just in front of the mechanism just described, is an upright frame 153 with a guide-box 154 on its top, opening in horizontal alinement with the initial-rolling shaft 128; this shaft traversing the open end in its lengthwise travel, and stopping very close to this open end and dwelling there, at the feed-end of the harp swing and delivery-end of the rack stroke, just described. The soap-chute 155 opens into the top of the guide-box 154 near the open end; and a cutter-bar 156 slides in the guide-box, being hollow and having on the under side of its top a blade 157 (Fig. 16) with its upwardly beveled edge pushed across the soap-chute entrance when the cutter-bar 156 is forced one way by the cutter-lever 158 having a fulcrum 159 in the frame 153 about midway of the height of the frame, and having slotted fork members at its upper end flanking the part of the cutter-bar 156 that extends out of the other end of the guide-box 154 and receiving trunnions 160 of the cutter-bar in the slots. The feed-bar 161 slides in the hollow cutter-bar 156, projecting past its connection with the lever 158, and has a pin engaging with the forked upper end of the feed-lever 162, which is fulcrumed coaxially with the cutter-lever 158. The cam-shaft 114, in front of the frame 113, has fixed on it two cams 164 and 165, and the cutter-lever 158 and feed-lever 162 have rollers on their lower end parts bearing on the peripheries of the respective cams. A guide-disk 166 separates the two peripheries and prevents interference between the lever rollers. The cutter cam 164, in front, has its periphery made up of two equal concentric sectors meeting in abrupt drops 167 (Fig. 16); and the feed cam 165 has diametrically opposite noses 168 with intervening parts of the periphery concentric. Tension springs 169 and 170, respectively, stretched between the levers 158 and 162 and a bracket 153' on the frame 153, hold these levers to the cam peripheries; the lever rollers bearing on the cams so that they push the cutter-bar 156 and feed-bar 161 toward the initial-rolling shaft 128 under the positive action of the cams, and return under the spring actions. The cutting action is slow and powerful; but the feeding action is relatively sudden, so as to be completed during the dwell of the initial-rolling shaft close to the guide-box open end.

This initial-rolling shaft 128 has, on its end part that is thus held before the guide-

box 154, a shorter finger 171 and a pair of longer fingers 172 and 172'; the shorter one being set into one flat side of the square shaft 128, and the other two, slightly spaced apart, being similarly set into the opposite flat side. The meshing of the pinion 143 and rack 142 is such that during the dwell of the shaft at the guide-box 154, the single finger 171 will be uppermost. The free end of the upper finger 171 and of the lowermost finger 172' is straight; but the free end of the upper finger 172 of the pair is curved upward. A flat upright stripper-plate 173 is on the front end of a hollow casing fixed to the harp 121 and surrounding the fingers, which latter recede behind this stripper-plate 173 when the shaft 128 carries the fingers backward. When these fingers are carried forward by this shaft 128, during the endwise forward thrust of the latter while it is dwelling at the end of the harp swing and pinion rotation, the lower pair of fingers 172 and 172' pass along a groove 96' across the top of the clip-table 96, just at the delivery-end side of the roller 94 bearing on said top; and as soon as the forward thrust is completed, they are carried toward the delivery end of the clip-table 96 by the harp swing, parallel with the table top, as pressed down on the rails 136 and 137 by the springs 130 in the harp members, and at the same time are rapidly rotated in the same direction by the oppositely traveling rack 142 acting upon the pinion 143. These operations are so timed relatively to the clip-chain operation, through the gearing including the sprocket-wheels 112 and 118, before described, that these fingers have begun their travel and rotation as just described, shortly before a pair of clip-jaws 102 and 103 has begun to descend below the clip-table 96 at the delivery end thereof; and the clip-driving mechanism and the folding-arm mechanism are so geared together that the folding-arm 72 completes its downward sweep just before the clip-jaws 102 and 103 pass above the clip-table 96 at the feed end thereof.

The frame 174 adjoins the clip-table 96 at the delivery end thereof. Brackets 175 are on the end of the folding-table 68, having on their ends the bearing-heads 176 vertically slotted with blocks 177 yieldably held down against the adjustable bottom 178 by springs 179 under screws 180 in removable tops 181. The first rolling-sheave 182 is journaled in the blocks 177 on a transverse axis slightly to the delivery-end side of the path of travel of the fingers across the clip-table and slightly thereabove. The bearing-heads 183 are mounted on the tops of the sides of the frame 174 adjacent to the clip-table end, and held for adjustment thereon by cap-screws 184 through longitudinal slots in the heads, which latter are

vertically slotted. Each head 183 comprises a block 185 yieldably held down against a lower adjusting screw 186 (Fig. 1) by a spring 187 on top, under a removable top 188 with a screw 189 for adjusting the spring. The second rolling-sheave 190 is journaled in the blocks 185 on a transverse axis. Close to the delivery-end sides of these heads 183 are similar heads 183' with 5 the third rolling-sheave 191 similarly journaled in its blocks. These heads 176, 183 and 183' are held adjustably in spaced relation by strut-bars meeting in turn-buckles 192 and 192'. The bearing-heads 10 183'' are located close to the delivery end of the frame 174, and are similar to the heads 183 and 183'. These heads 183'' are adjusted toward the delivery end by wedges 193 pushed up between them and abutments 15 194 by screws 195 (Fig. 1.) The blocks 185'', 185 of this head are the journal bearings of the fourth rolling-sheave 196. Between the third and fourth sheaves 191 and 196 is the intermediate rolling-sheave 20 197 journaled in blocks 198 sliding in longitudinal slots of short arms 199 pivoted to the bases of the terminal bearing-heads 183'' and inclined up therefrom; the blocks being yieldably held outward and upward 25 in the arms by springs 200, and the arms being yieldably held down by springs 201 compressed between them and the heads 183'' and adjustably held up against these springs 201 by screws 202 passing up through extensions of the abutments 194. The middle 30 preliminary-rolling belt 203 passes around the first and third sheaves 182 and 191, and the side preliminary rolling belts 204 pass around the first and second sheaves 182 and 190, to the rear and in front of the middle belt 203. The side final-rolling belts 205 pass around the third and fourth sheaves 191 and 196, and the middle final-rolling belt 206 passes around the fourth sheave 40 45 50 196 and around the intermediate sheave 197. These belts are kept tight by means of the various adjusting means just before described, and are yieldable upwardly as permitted by the upper springs of the various sheave bearings as described.

The second sheave 190 is driven by a sprocket-chain 207 around a sprocket-wheel 208 fixed on the projecting front end part of the sheave shaft and around a sprocket-wheel 209 on a lower transverse shaft 210 with a friction-disk 211, across which extends a shaft 212 with a friction-wheel 213 journaled thereon and contacting with the face of the disk 211 and the face of an opposed friction-disk 214 on a transverse shaft 215 with sprocket-wheels 216 and 217 and pressed toward the wheel 213 by a spring 218. These various shafts are journaled in suitable forward extensions of the frame 174; and the shaft 212 is adjustable lengthwise by a hand-wheel 219 in a fork on one of these extensions, the shaft carrying the wheel 213 by flanges 220 flanking the wheel. One of the sprocket wheels 217 is driven along with the previously described mechanisms as will later be described; and the other wheel 216 is to drive later described mechanism. The friction-disk and wheel permit variation of the speeds of all of the belts, thus driven through the medium of the sheave 190, relatively to the other mechanisms. The driving sprocket-chain 207 is kept tight by the idler sprocket-wheel 221 on the arm 222 pivoted on the side of the frame 174 and pressed by a spring 223 around its pivot.

Over the space between the third sheave 191 and the intermediate sheave 197 is a transverse bridge 224, with bearings for shafts 225 and 226 parallel in a horizontal plane and extending transversely and having concentrically fixed to them, respectively, the tape-cutting roll 227 and the wetting or moistening roll 228; the former next to the delivery end. These shafts 225 and 226 also have fixed on them the gears 229 and 230, respectively, of equal diameter and meshing together; and the cutting-roll shaft 225 projects forwardly and has fixed on it the sprocket-wheel 231 with a sprocket-chain 232 around it and around a lower sprocket-wheel 233 on a transverse shaft 234 with the friction-disk 235, across which extends a shaft 236 with a friction-wheel 237 journaled thereon and contacting with the face of the disk 235 and with the face of an opposed friction-disk 238 on a transverse shaft with a sprocket-wheel 239 and pressed toward the wheel 237 by a spring 240. These various shafts are journaled in suitable forward frame extensions like the rolling-mechanism-driving shafts; and the shaft 236 is adjustable lengthwise by a hand-wheel 241 in a fork on one of these extensions, the shaft carrying the wheel 237 by flanges 242 flanking the wheel. A sprocket-chain 243 passes around the wheel 239 and around the previously described wheel 216, and is kept tight by an idler sprocket-wheel 244 on a block 245 sliding up and down in a slot in a part of the frame 174 and pulled down to bear the wheel on top of the lower stretch of the chain 243 by a tension spring 246 at the bottom of the frame (Fig. 1.) The frictionally driving mechanism just described permits variation of the speed of the cutting-roll 227 and moistening roll 228 relatively to the other mechanisms; the cutting-roll driving the moistening-roll through the medium of their gears 229 and 230.

The tape-cutting roll 227 has offsets 247 at its ends, and the moistening-roll 228 has corresponding flanges 248 at its ends, fitting in the offsets 247. The cutting-roll 227 has a slot extending radially inward from one

side, in which is a blade 249 with its cutting edge extending past the roll periphery from one offset 247 to the other, and yieldably pressed radially outward in its slot by a flat 5 arched spring 250 across the bottom of the slot and adjustably held toward the back edge of the blade 249 by a screw 251 passed radially through into the slot from the opposite side of the roll (Fig. 34.) The blade 10 249 is prevented from being forced entirely out of the roll by side-plates 252 screwed to the roll face at opposite sides of the slot and having their edges engaging the opposite sides of the bevel of the blade. (Fig. 15 32.)

The wetting or moistening roll 228 is hollow, and the rear section of its shaft is a tube 253 screwed into the roll end and entering a connection-head 254 through a stuffing-box 20 255 (Fig. 33,) this head 254 being mounted on a bracket 256 at the back of the frame 174 and having a pipe 257 leading down into its top from a reservoir 258 which the pipe 257 supports at its upper end, with a 25 cock 259 in the pipe (Fig. 1.) The moistening roll 228 has a segmental recess in its periphery, deep enough to admit plates 260 across the roll from one flange 248 to the other; the plates 260 having their adjacent 30 edges beveled back from each other radially inwardly and holding between them a strip 261 of soft material, such as felt, and these plates being held in place by screws 262 (Fig. 32.) The wall of the roll 228 under 35 the segmental recess has perforations 263, forming liquid-passing openings from the hollow interior of the roll out into the recess and around and between the plates 260 and strip 261. The rolls 228 and 227 are so 40 geared together by their gears 229 and 230 that the edge of the blade 249 will register with the soft strip 261 at each revolution of the rolls, and the plates 260 extend out slightly past the face of the roll 228.

45 The tape-reel 264 is journaled in a post 265 extending up from the rear of the frame 174 (Fig. 1) and having just below the reel an extension in which are journaled the guiding and flattening rolls 266 and 267 on 50 transverse axes in vertical registry with the cutting and moistening rolls 227 and 228, respectively. The roll 266 has its periphery transversely convex, and the roll 267 has its periphery correspondingly concave 55 and receiving the convex periphery of the other roll.

Under these cutting and moistening rolls 227 and 228 are bars 268 extending across the frame 174 and supporting transverse 60 upright guide-plates 269 and 270, with a slight space between their upright plane adjacent surfaces (Fig. 32,) these plates extending up close to the adjacent parts of the rolls 227 and 228 and their intervening space 65 being substantially along a vertical tangent

to these rolls. The lower end of the first plate 269 is slightly above the plane of the lower stretches of the side final-rolling belts 205, and is preferably beveled. The second plate 270, nearer the delivery end, terminates 70 somewhat higher, and has hinged to it the lapping-plate 271, normally depending under the pressure of a U-shaped spring 272 fixed on the plate 270, but yielding upwardly toward the delivery end of the machine upon 75 pressure in that direction. This lapping-plate extends down close to the flat upper surface of the rolling-table 273, which surface is substantially in the same plane with 80 and is substantially continuous with the top of the clip-table 96, and opens outwardly under the fourth sheave 196 and the belts 205 and 206.

It will be understood that the frame 174 and the clip-table and soap-inserting and 85 initial-rolling mechanism frame structures and associated parts may be continuations of the pedestal 1, instead of being separate structures mounted on the bed-plate 1' as 90 herein shown.

The mechanisms are all driven from one of the pedestal shafts, preferably the shaft 15 under the cutter-feeding mechanism, having a sprocket-wheel 274 fixed on it inside the pedestal 1 with a chain 275 around it 95 and around the sprocket-wheel 276 on the shaft 15 under the second-creasing rolls, which has another sprocket-wheel 277 with a chain 277' around it and around a sprocket-wheel 278 fixed on the shaft 15 under the first-creasing rolls, these various rolls being 100 driven by the respective shafts 15 as was previously described. The shaft 15 under the cutter-feeding rolls has a smaller sprocket-wheel 279 fixed on it between the pedestal sides, with a chain 280 around it and around a sprocket-wheel 281 on the shaft 282 which also has fixed to it the before described sprocket wheel 112; this shaft 282 thus 105 driving the clip-table and soap-feeding and initial-rolling mechanisms by gearing as has been described. It also drives the mechanism for giving to the folding arm 72 its transverse withdrawing and inserting motions; the swinging of this arm being caused 110 by the rotation of the cutter, as was described. The shaft 282 has another sprocket wheel 283 fixed on its forward extension, with a chain 284 around it and around the before mentioned sprocket wheel 217, by 115 which the final-rolling and cutting and moistening mechanisms are driven, as has just been described.

It will be understood that any one of the shafts 15 may be utilized as the driving shaft for the entire machine; the one under the cutter-feeding rolls being preferred, as it is intermediately located and distributes the power more evenly to the respective end parts of the machine. The driving of this, or any other shaft utilized 120

as the machine-driving shaft, may be by a pulley thereon, with a belt, or by a motor suitably geared thereto, or in any other suitable manner; these methods being well known and not requiring illustration herein.

Operation.—The toweling being fed in a flat web to the first-creasing rolls 4 and 7, it is given three longitudinal creases 285, 285' and 285'', equally spaced from each other and from the lateral edges of the web. The folding-box sections 29 and 32 are swung open, and this creased web is passed around the folding-box core 28, with the middle crease 285 under the bottom corner or angle of the core, and the creases 285' and 285'' along the lateral angles of the core, while the lateral edges of the web are made to come very close together along the top angle of the core; the parts being proportioned to effect this result. This condition of the web is seen in Fig. 9.

The folding-box sections 29 and 32 are then closed together and latched by their shackles 30; holding the folded web around the core 28 in the slight space all around between the sections and the core. The convergence of the folding-box top and bottom parts in an upright plane and the corresponding divergence in a transverse plane are so proportioned that the folded web emerges from the delivery end of the box with its upper and lower folds fully distended in almost flattened condition, while the first-creasing rolls 4 and 7 are located the proper distance from the feed end and the second-creasing rolls 36 and 37 are located the proper distance from the delivery end of the forming-box to have the web evenly stretched from its initial flat condition to its rectangular cross-section in the folding-box entrance, and from there to its folded flat condition between the rolls 36 and 37, between which it is passed after emerging from the folding-box. In passing between these rolls 36 and 37, the web becomes completely folded as seen in Fig. 10, with the laterally outer parts folded in upon the middle parts, and having the lateral edges of the web close together along the middle line of the web, along which is the middle one 285 of the first creases given to the web between the rolls 4 and 7. The second-creasing rolls recrease the web along this middle crease 285; or, it may be said, they conserve this middle crease, by virtue of their middle ridge and groove. This middle crease 285 is conserved for the second folding, effected by passing the web between the upright final flattening rolls 41 and 43, which are located the right distance from the rolls 36 and 37 to permit the web to pass from its flat folded transverse position into an additionally folded upright position with all parts of the web evenly stretched. This additional folding results in the folded-in lat-

eral parts of the web being brought together, as in Fig. 11, so that the strip now consists of four thicknesses of the material, with two of the original creases 285' and 285'' as one edge and the middle one of those creases 285 70 forming the opposite edge of the strip. Thus, no raw, unfolded edges of the web are exposed.

These upright rolls 41 and 43 are far enough from the cutter-feeding rolls 50 and 51 for the web, now having its lengthwise folding completed, to pass from its upright position to a transverse one between these rolls 50 and 51 with all parts of the web evenly stretched. These rolls 50 and 51 80 simply pull the longitudinally folded web from the other rolls and extend it over the fixed blade 60 during the rotation of the blade 57 away therefrom and around thereto; the gearing of the mechanisms being 85 such that the right length of folded web will be projected past this blade 60 over the folding-table 68 by the uniform rotation of the rolls during that period of uniform rotation of the cutter, and so that the blade 57 90 will cooperate with the blade 60 at the time this extension is completed. The severed piece 286 then falls evenly on the folding-table 68, which has its opening between its two parts 68' and 68'' so located that it will 95 be under the middle of the piece 286. This piece will now appear as seen in Fig. 11, with cleanly cut ends having the raw edges of the material exposed, and with its longitudinal edges composed of folds. 100

It will be understood that in preparing the machine for operation, the web is passed by hand through all of the mechanisms as just described, and then when the machine is started the rolls, especially if their peripheries be scored, will grip and feed the material continuously, evenly and at uniform speed, without any appreciable excessive strains at any point in the material. The first revolution of the cutter will sever whatever projection of material there is at the passage of the blade 57, squaring the advance end of the first piece, after which the pieces will be severed at a regular rate; a succeeding piece beginning to extend past the fixed 105 blade 60 just as soon as the preceding piece 110 has been severed.

By proper proportion of the gearing, the folding-arm 72, which has been elevated and slid back over the folding-table 68, descends as soon as the piece 286 drops onto the table 68, and its folding-bar 71 engages its narrow lower edge transversely of the piece 286, forcing the middle of the piece down into the folding-table opening, and, continuing to draw this middle fold 287 through the opening, folds the piece transversely with its two cut ends 288 together as seen in Fig. 17, where the folding bar 71 is indicated in its position inside the fold 287. 10065 10070 1

folding-bar has passed the fold 287 out past the roller 94, with this roller pressed down by the spring 95 and gripping the fold, the folding-bar 71 is withdrawn transversely 5 forwardly by the mechanism sliding the folding-arm 72 on its shaft as before described. As soon as this withdrawal is completed, one of the pairs of jaws 102 and 103 10 grips the fold 287 and begins pulling the folded piece along the clip-table 96, with the piece kept tightly stretched by the resistance of the spring-pressed roller 94.

In the meantime, the folding-bar 71 is being swung up and slid back over the folding-table 68 to descend on the next piece 286 15 which has been severed by the blades 57 and 60.

Also, during this time, the initial-rolling shaft 128 has been stopped with its fingers 171, 172 and 172' opposite the open end of the guide-box 154, with the finger 171 above and the fingers 172 and 172' below; and the soap, in a long narrow bar descending by gravity through the chute 155 so 20 that its lower end rests on top of the feed-bar 161, has dropped into the space adjacent the guide-box open end when the feed-bar is withdrawn by its spring 170 as permitted by the drop from the cam-nose 168, 25 after which the cutter-bar 156 has been pushed in by the eccentric sector of the cam 164 and its blade 157 has severed the soap portion 289, after which the next cam-nose 168 caused the feed-bar 161 to push the 30 severed piece 289 out between the upper finger 171 and the upper one 172 of the lower pair of fingers, which grip the piece 289 by virtue of their resiliency; the cutter-bar 156 being again withdrawn and the 35 soap strip again resting on top of the feed-bar 161, ready for the next soap-feeding operation. The placing of the piece of soap 289 between the fingers will have been completed and the inserting-arm 131, under the 40 action of the cam 122, will be sliding the initial-rolling shaft 128 forwardly across the stretched piece of towel material 286; by which action the lowest finger 173 is projected under the piece 286, in the transverse slot 96', while the upper fingers 172 and 171 carry the piece of soap 289 over the piece 286. This action will be completed just before the piece 286 has been 45 dragged far enough by the jaws 102 and 103 to release the ends 288 of the piece 286 from under the roller 94.

As this release occurs, the crank-wrist 126 passes the center and begins to swing the harp 121 toward the delivery end, and the crank-wrist 150 completes its travel in the yoke-offset 152 and begins to pull the rack 142 toward the free end of the machine. The resultant of these motions is to sweep the initial-rolling shaft 128 along 50 the clip-table 96 and whirl it more rapidly

than it would be whirled from simply rolling along. The ends 288 of the piece of towel material 286 being held between the pair of fingers 172 and 173, this piece is wound around the upper one of these fingers 70 172 and the single uppermost finger 171 and the piece of soap 289 between these fingers 171 and 172; the accumulating roll immediately coming between the three preliminary-rolling belts 203 and 204 above and the clip-table top below. These belts 203 and 204, with their lower stretches thus in contact with the initially-rolled package 290, now in the condition shown in Fig. 19; and traveling toward the delivery end, tend 75 to roll the package in that direction, while the rapidly whirling fingers tend to tighten the grip of the inner turns of the towel piece around the soap piece.

As soon as this control of the package 80 by the belts 203 and 204 is established, the cam 122 and inserting-arm 131 begin to withdraw the still whirling initial-rolling shaft 128 and its fingers 171, 172 and 173 85 from the package 290; this withdrawal being completed by the time the harp 121 has swung the shaft 128 to the delivery end of its travel, so that the shaft 128 may be swung back, free of engagement with the advancing package, ready for the next soap-90 inserting and initial-rolling operation. As the jaws 102 and 103 reach the extension 106', or piece 106^a, as the case may be, the jaws open, releasing the fold 287 of the 95 towel piece 286, which piece has been kept tightly stretched while being rolled up from its opposite cut ends 288 by the initial and preliminary-rolling devices. The package 290, now with its preliminary rolling completed, is passed by the middle preliminary-rolling belt 203 under the side final-rolling belts 205, which leave the middle of the 100 package 290 free for the passage of the tape therearound.

Tape 291 with dry adhesive substance on 110 one side is fed from the reel 264 (Fig. 1) down between the convex and concave rolls 266 and 267, which flatten the tape from the warped condition that its adhesive usually gives to it, and guide the tape down between the cutting-roll 227 and the moistening-roll 228, with the adhesive next to the latter roll; and from these rolls the tape passes down between the guide-plates 269 and 270, to depend across the path of the advancing 115 rolling package. In its passage between the cutting-roll 227 and the moistening-roll 228, the blade 249 has severed the piece of tape 292, while the extended plates 260 have moistened the adhesive substance at both sides 120 of the cut, during the cutting operation. The severed piece of tape 292 will thus have adhesive areas 293 and 294 adjacent its upper and lower ends, the lower area having been 125 made adhesive at the time the last preceding 130

piece was severed, and the upper area being so treated at the present severance. These adhesive areas being presented toward the advancing rolling package 290, and the 5 severed piece of tape being still held by its upper end between the moistening-roll extension 260 and the face of the cutting-roll side-plate 252 when the package 290 meets the lower-end adhesive area 294, this will be 10 attached to the outer surface of the package 290, which, continuing to be rolled by the belts 205, will force the lapping-plate 271 upward, and this plate, under its spring-pressure, will bear against the tape piece 292, 15 and the latter, now released by the cutting-roll 227 and moistening-roll 228, will be wound around the rolling package 290 until the opposite moistened end-area 293 is swept around and lapped over the first-attached 20 end part of the tape piece 292 by the still bearing lapping-plate 271, and, by the spring-pressure thereof, is pressed tightly against and attached to the opposite attached end part, completing the attachment 25 of the binding tape. The belts 205 now continuing to roll the package, bring it under the middle final-rolling belt 206, which, strongly pressed down by the springs 201, gives to the middle part of the package 290 30 and the tape 292 therearound a thorough final-rolling, while the side final-rolling belts are still firmly rolling the end parts of the package 290. These three belts 205 and 206 roll the completed package 290 out under 35 the terminal sheave 196, to drop from the end of the rolling table 273 into a suitable receptacle, or to be received by any desired additional mechanism, as for instance, a machine for packing the completed packages 40 into cartons or the like. The appearance of the completed package 290 is seen in Fig. 29.

The piece of soap 289, as seen in Fig. 16, is of square cross-section, preferably being, in practice, about three-tenths inch square, 45 and, as seen in Fig. 15, is considerably longer than its cross-sectional dimensions, being preferably about three-fourths inch long. I prefer to feed two webs of towel material together, so that the package will contain 50 two towels together with the piece of soap. These two thicknesses of towel material, however, are acted upon throughout the operation of the machine, as before described, exactly as upon a single thickness, 55 except that the two have the added strength to withstand the strains of the operations. For this reason, and for simplicity, I have described the combined thicknesses as a web, and the severed combined thicknesses as 60 a piece, although it will be understood that such a web may consist of two thicknesses as preferred, or of more thicknesses if a greater number of towels are desired in the package.

65 I prefer the soap piece of square, sym-

metrical cross-section because it imparts to the completed package a more nearly cylindrical shape than a flat piece such as disclosed and claimed in my copending application hereinbefore referred to, while the flat piece may be more desirable by some users. Either shape, or any other shape of soap piece is within the scope of said application, and is adapted to be packaged by the present machine. Or any other object 70 may be wrapped in similar or other sheet material with the material in one or more thicknesses, by this machine or convenient modifications thereof. Also, the machine may be used merely to roll one or more 75 thicknesses of sheet material into convenient packages, either for dispensing in a machine like that of my other mentioned copending application or other suitable machine, omitting the soap or other object. 80 Such operation would dispense with the use of the feeding and severing mechanism here exemplified for the soap; but the initial-rolling function of the shaft 128 and associated parts would remain. Moreover, soap or 85 other objects may be fed to the proper parts of the machine as individual objects, without the severance; or the pieces of sheet material may be fed as individual pieces, dispensing with the continuous feeding and folding 90 mechanism, and such pieces, whether fed continuously in web form and severed by the machine, or fed individually without the continuous feeding mechanism, may have 95 some or all of their folds dispensed with, as 100 may be desired under some conditions. The preferred package, herein shown as an example, is more suitable for mechanical dispensing because it exposes no raw sheet-material edges to be torn and rumpled in the 105 machine, giving the package an undesirable appearance and tending to clog in the machine. Likewise, the very firm formation of the package, by rolling its material while tightly stretched, with the preferred whirling motion, and by tightly rolling it finally, 110 as by the belts, makes the package especially adapted to mechanical dispensing, because the machine, even with special provisions for operating on somewhat yielding objects, 115 as is the machine of my copending application, requires the package, if of inherently soft sheet material, such as crêpe-paper toweling, to be formed as tightly as is practicable. But it will be understood that these provisions are not always essential, depending upon the methods of distribution of the packages; and my packaging machine, as herein disclosed, is adaptable for making 120 packages more or less firmly rolled or otherwise compacted to the degree that may be required.

In the binding of the packages, these may be secured against unrolling or opening by means other than the tape, or the tape may 125

be otherwise than adhesively secured; or tape not initially supplied with adhesive material may have the adhesive material applied to it by the moistening-roll, as by supplying such material to the roll from the reservoir instead of simply supplying water, as is herein described as the preferred example. Any one or several of these different operations may be substituted for the exemplified ones without altering the general principles of my invention, and without necessarily modifying certain of the several departments thereof, as will be understood.

The adaptability of the machine, and of its product, and of the methods involving the use of the machine in varying the product is suggested by these instances just mentioned, and makes it apparent that variations in the construction and arrangement of the various parts may occur under varying conditions, and therefore, while certain constructional details, operations, and resultant product are deemed preferable in connection with my invention, and I have shown and described these rather specifically in elucidating the construction and use of my invention, as is required, I do not wish to be understood as being limited to such precise showing and description, but having thus fully described my invention, what I claim as new and desire to secure by Letters Patent is:

1. In a machine of the character described, means for feeding successive pieces of sheet material, means for feeding successive objects to the respective pieces, means for compressing the pieces around the objects, and means acting on said pieces only after their compression, for securing the pieces in their compressed condition.

2. In a machine of the character described, means for feeding successive pieces of sheet material, means for feeding successive objects to the respective pieces, means for rolling the pieces around the objects, and means acting on said pieces only after they are rolled, for securing the pieces in their rolled condition.

3. In a machine of the character described, means for feeding a web, means for severing said web, means for feeding an article to the severed web, means for forming said severed web in a plural-ply wrapper about said article, and means acting on said severed web only after it is thus formed, for securing said severed web in its formed condition.

4. In a machine of the character described, mechanism for feeding successive pieces of sheet material longitudinally, means for feeding successive objects transversely to the respective pieces, longitudinally-acting means for compressing the pieces around the objects and means for securing the pieces in their compressed condition.

5. In a machine of the character described,

means for feeding a continuous web, means for longitudinally folding said web, means for severing the longitudinally folded web, means for forming said severed web into reduced longitudinal dimensions by a plurality of transverse bends or folds, and means acting on said severed web only after it is thus formed, for securing said web in its formed condition.

6. In a machine of the character described, continuously operating means for feeding successive pieces of sheet material, intermittently operating means for feeding successive objects to the respective pieces, continuously operating means for compressing the pieces around the objects, and means acting on said pieces only after their compression, for securing the pieces in their compressed condition.

7. In a machine of the character described, continuously operating means for feeding successive pieces of sheet material, intermittently operating means for feeding successive objects to the respective pieces, continuously operating means for rolling the pieces around the objects, and means acting on said pieces only after they are rolled, for securing the pieces in their rolled condition.

8. In a machine of the character described, web-feeding mechanism, means for severing successive pieces from the fed web, means for feeding successive objects to the respective pieces, means for compressing the pieces around the objects, and means acting on said pieces only after their compression, for securing the pieces in their compressed condition.

9. In a machine of the character described, web-feeding mechanism, means for severing successive pieces from the fed web, means for feeding successive objects to the respective pieces, means for rolling the pieces around the objects, and means acting on said pieces only after they are rolled, for securing the pieces in their rolled condition.

10. In a machine of the character described, web-feeding mechanism, means for severing successive pieces from the fed web, means for severing and feeding successive objects to the respective pieces, means for rolling the pieces around the objects, and means acting on said pieces only after they are rolled, for securing the pieces in their rolled condition.

11. In a machine of the character described, web-feeding mechanism, means for severing successive pieces from the fed web, means for feeding successive objects to the respective pieces transversely of the web travel, means for rolling the pieces around the objects, and means acting on said pieces only after they are rolled, for securing the pieces in their rolled condition.

12. In a machine of the character described, web-folding mechanism, means for

- severing successive pieces from the folded web, means for feeding successive objects to the respective pieces, means for rolling the pieces around the objects, and means for securing the pieces in their rolled condition.
13. In a machine of the character described, means for folding a web longitudinally, means for severing successive folded pieces from the folded web, means for feeding successive objects to the respective pieces, means for rolling the pieces around the objects, and means for securing the pieces in their rolled condition.
14. In a machine of the character described, means for folding laterally outer parts of a web inward upon the middle part of the web, means for longitudinally folding the thus folded web with the folded-in parts together, means for severing successive folded pieces from the folded web, means for folding these folded pieces transversely, means for feeding successive objects to the respective pieces, means for rolling the pieces around the objects, and means for securing the pieces in their rolled condition.
15. In a machine of the character described, web-feeding mechanism, means for severing successive pieces from the fed web, means for rolling the severed pieces, and means acting on said pieces only after they are rolled, for securing the pieces in their rolled condition.
16. In a machine of the character described, means for folding a web longitudinally, means for severing successive folded pieces from the folded web, means for rolling the folded and severed pieces, and means for securing the pieces in their rolled condition.
17. In a machine of the character described, means for folding laterally outer parts of a web inward upon the middle part of the web, means for longitudinally folding the thus folded web with the folded-in parts together, means for severing successive folded pieces from the folded web, means for folding these folded pieces transversely, means for rolling the severed and folded pieces, and means for securing the pieces in their rolled condition.
18. In a machine of the character described, means for feeding pieces of sheet material, means for rolling the pieces, and means acting on said pieces only after they are rolled, for binding the pieces in their rolled condition.
19. In a machine of the character described, means for feeding pieces of sheet material, means for folding the pieces thus fed, means for rolling the folded pieces, and means for binding the pieces in their rolled condition.
20. In a machine of the character described, means for feeding folded pieces of sheet material, means for additionally fold-
- ing the pieces thus fed, means for rolling the pieces thus additionally folded, and means for binding the pieces in their rolled condition.
21. In a machine of the character described, means for feeding plurally folded pieces of sheet material, means for additionally folding the pieces thus fed, means for rolling the pieces thus additionally folded, and means for binding the pieces in their rolled condition.
22. In a machine of the character described, means for feeding pieces of sheet material, means for rolling the pieces around respective objects to be wrapped therein, and means acting on said pieces only after they are rolled, for binding the pieces in their rolled condition.
23. In a machine of the character described, means for feeding pieces of sheet material, means for folding the pieces thus fed, means for rolling the folded pieces around respective objects to be wrapped therein, and means for binding the pieces in their rolled condition.
24. In a machine of the character described, means for feeding folded pieces of sheet material, means for additionally folding the pieces thus fed, means for rolling the thus additionally folded pieces around respective objects to be wrapped therein, and means for binding the pieces in their rolled condition.
25. In a machine of the character described, means for feeding plurally folded pieces of sheet material, means for additionally folding the pieces thus fed, means for rolling the thus additionally folded pieces around respective objects to be wrapped therein, and means for binding the pieces in their rolled condition.
26. In a machine of the character described, means for feeding pieces of sheet material, means for rolling said pieces, means for feeding binding material to the rolled pieces, and means for securing said binding material around the rolled pieces.
27. In a machine of the character described, means for feeding pieces of sheet material, means for rolling said pieces, means for severing and feeding binding material to the rolled pieces, and means for securing said binding material around the rolled pieces.
28. In a machine of the character described, means for feeding pieces of sheet material, means for rolling said pieces, means for rendering binding material adhesive and feeding said binding material to the rolled pieces, and means for pressing together adhesive parts of said binding material around the rolled pieces.
29. In a machine of the character described, means for feeding pieces of sheet material, means for rolling said pieces,

- means for rendering binding material adhesive and severing and feeding said binding material to the rolled pieces, and means for pressing together adhesive parts of said binding material around the rolled pieces.
30. In a machine of the character described, means for feeding successive pieces of sheet material, means for feeding successive objects to the respective pieces, means for rolling the pieces around the objects, means for feeding binding material to said pieces, and means for securing binding material around the rolled pieces.
31. In a machine of the character described, means for feeding successive pieces of sheet material, means for feeding successive objects to the respective pieces, means for rolling the pieces around the objects, means for severing and feeding binding material to said pieces, and means for securing the binding material around the rolled pieces.
32. In a machine of the character described, means for feeding successive pieces of sheet material, means for feeding successive objects to the respective pieces, means for rolling the pieces around the objects, means for rendering binding material adhesive and feeding said binding material to said pieces, and means for pressing together adhesive parts of said binding material around the rolled pieces.
33. In a machine of the character described, means for feeding successive pieces of sheet material, means for feeding successive objects to the respective pieces, means for rolling the pieces around the objects, means for rendering binding material adhesive and severing and feeding said binding material to said pieces, and means for pressing together adhesive parts of said binding material around the rolled pieces.
34. In a machine of the character described, means for folding laterally outer parts of a web inward upon the middle part of the web, means for longitudinally folding the thus folded web with the folded-in parts together, means for severing successive folded pieces from the folded web, means for folding these folded pieces transversely, means for feeding successive objects to the respective pieces, means for rolling the pieces around the objects, means for severing and feeding binding material to said pieces, and means for securing said binding material around the rolled pieces.
35. In a machine of the character described, means for folding laterally outer parts of a web inward upon the middle part of the web, means for longitudinally folding the thus folded web with the folded-in parts together, means for severing successive folded pieces from the folded web, means for folding these folded pieces transversely, means for severing and feeding binding material to said pieces, and means for securing said binding material around the rolled pieces.
- versely, means for rolling said pieces, means for severing and feeding binding material to said pieces, and means for securing said binding material around the rolled pieces.
36. In a machine of the character described, means for folding laterally outer parts of a web inward upon the middle part of the web, means for longitudinally folding the thus folded web with the folded-in parts together, means for severing successive folded pieces from the folded web, means for folding these folded pieces transversely, means for rolling the pieces, means for rendering binding material adhesive and severing and feeding said binding material to said pieces, and means for pressing together adhesive parts of said binding material around the rolled pieces.
37. In a machine of the character described, means for forming parallel longitudinal creases in a web, forming means having angles extending along the creases of the web, converging in one plane and diverging in another plane in the direction of web travel, means for drawing the web around said forming means, folding the web at said angles and flattening the thus folded web; means for severing successive pieces from the folded and flattened web, means for feeding successive objects to the respective pieces, means for passing the pieces around the objects, and means for securing said pieces therearound.
38. In a machine of the character described, means for forming parallel longitudinal creases in a web, forming means of quadrangular cross-section having its angles extending along the creases of the web, converging in one plane and diverging in another plane in the direction of web travel, means for drawing the web around said forming means, folding the web at said angles and flattening the thus folded web, means for severing successive pieces from the folded and flattened web, means for feeding successive objects to the respective pieces, means for passing the pieces around the objects, and means for securing said pieces therearound.
39. In a machine of the character described, means for forming parallel longitudinal creases in a web, forming means comprising a core having angles extending along the creases of the web, converging in one plane and diverging in another plane in the direction of web travel, and means surrounding and conforming to said core but spaced therefrom to admit the web through said forming means around the core, means drawing the web through said forming means, folding the web at said angles and flattening the thus folded web, means for severing successive pieces from the folded and flattened web, means for feeding successive objects to the respective pieces,

means for passing the pieces around the objects, and means for securing said pieces therearound.

40. In a machine of the character described, means for forming parallel longitudinal creases in a web, forming means having angles extending along the creases of the web, converging in one plane and diverging in another plane in the direction 10 of web travel, means drawing the web around said forming means, folding the web at said angles and flattening the thus folded web, and having means forming a longitudinal crease in the thus folded and flattened 15 web, means further longitudinally folding the web along the crease and flattening the thus folded web, means for severing successive pieces from the folded and flattened web, means for feeding successive objects to 20 the respective pieces, means for passing the pieces around the objects, and means for securing the pieces therearound.

41. In a machine of the character described, forming means for forming a web to 25 fold longitudinally, having angles extending along the web, converging in one plane and diverging in another plane in the direction of web travel, means drawing the web around said forming means, and means further longitudinally folding the web and flattening the thus folded web.

42. In a machine of the character described, means for folding a web longitudinally, means for severing successive folded 35 pieces from the folded web, means receiving said pieces and having an opening opposite a median part of the received piece, a folding element to press this part of the piece through said opening, mechanism imparting 40 to said element its pressing motion through said opening and a return motion outside said opening, means withdrawing said piece from said opening, means for feeding successive objects to the withdrawn pieces, 45 means for rolling the pieces around the objects, and means for securing the pieces in their rolled condition.

43. In a machine of the character described, means for folding a web longitudinally, means for severing successive folded pieces from the folded web, means receiving said pieces and having an opening opposite a median part of the received piece, a folding element to press this part of the piece 55 through said opening, mechanism imparting to said element its pressing motion through said opening and a return motion outside said opening, means withdrawing said piece from said opening, means for rolling the withdrawn pieces, and means for securing the pieces in their rolled condition.

44. In a machine of the character described, means to feed successive pieces of sheet material, means to hold said pieces, 60 rotary means having elements to straddle the

held piece edgewise thereof, and a third element spaced from said straddling elements, means to insert successive objects between this third element and the adjacent straddling element, mechanism to project 70 said rotary means with its straddling elements astraddle of said piece, means to rotate said projected rotary means, initially 75 rolling said piece around the inserted object, and to withdraw said rotary means from the initially-rolled piece, means contacting with said piece during the withdrawal of said means and continuing the rolling of said piece, and means for securing the piece in its rolled condition. 80

45. In a machine of the character described, means to feed successive pieces of sheet material, means to hold said pieces, rotary means having elements to straddle the held piece edgewise thereof, and a third 85 element spaced from said straddling elements, means to sever successive objects and insert said objects between this third element and the adjacent straddling element, mechanism to project said rotary means 90 with its straddling elements astraddle of said piece, means to rotate said projected rotary means, initially rolling said piece around the inserted object, and to withdraw said rotary means from the initially-rolled 95 piece, means contacting with said piece during the withdrawal of said means and continuing the rolling of said piece, and means for securing the piece in its rolled condition.

46. In a machine of the character described, means to feed successive pieces of sheet material, means to hold said pieces, means to partially withdraw and temporarily stretch the respective held pieces, means for applying successive objects to 100 the respective stretched pieces, means for rolling the stretched pieces around the respective objects, and means for securing said pieces in their rolled condition. 105

47. In a machine of the character described, means to feed successive pieces of sheet material, means to hold said pieces, a longitudinally traveling gripper to grip and partially withdraw and temporarily stretch the respective held pieces, means for applying successive objects to the respective stretched pieces, means for rolling the stretched pieces around the respective objects, and means for securing said pieces in their rolled condition. 110 115

48. In a machine of the character described, means to feed successive pieces of sheet material, means to hold said pieces, a longitudinally slotted table, an endless flexible element traveling lengthwise of said table from the feeding and holding means, a gripper carried by said element along said slot to grip and partially withdraw and temporarily stretch the respective held pieces, means for rolling the respective 125 130

stretched pieces, and means for securing said pieces in their rolled condition.

49. In a machine of the character described, means to feed successive pieces of sheet material, means to hold said pieces, a longitudinally slotted table, an endless flexible element traveling lengthwise of said table from the feeding and holding means, a pair of jaws carried by said element along the slot of said table, one of said jaws having an extension, a member along said element, engaged by said extension to cause said jaws to grip and partially withdraw and temporarily stretch the respective held pieces, means for rolling the respective stretched pieces, and means for securing said pieces in their rolled condition.

50. In a machine of the character described, means to feed successive pieces of sheet material, means to hold said pieces, a longitudinally slotted table, an endless flexible element traveling lengthwise of said table from the feeding and holding means, a gripper carried by said element along the slot of said table to grip and partially withdraw and temporarily stretch the respective held pieces, rotary means having elements to straddle the stretched piece edge-wise thereof, mechanism to project said rotary means with its straddling elements astraddle of said piece, means to rotate said projected rotary means, initially rolling said piece, and to withdraw said rotary means from the initially-rolled piece, means contacting with said piece during the withdrawal of said rotary means and continuing the rolling of said piece, and means for securing said piece in its rolled condition.

51. In a machine of the character described, means to feed successive pieces of sheet material, means to hold said pieces, a circuit-traveling element and a plurality of grippers successively carried by said element to grip and partially withdraw and temporarily stretch respective ones of the pieces, means for rolling the respective stretched pieces, and means for securing said pieces in their rolled condition.

52. In a machine of the character described, means to feed successive pieces of sheet material, means to hold said pieces, a circuit-traveling gripper to grip and partially withdraw and temporarily stretch the successive held pieces, means for rolling the pieces while stretched, and means for securing said pieces in their rolled condition.

53. In a machine of the character described, means to feed successive pieces of sheet material, means to hold said pieces, a spring-closed gripper, cam-opened to grip and partially withdraw and temporarily stretch the successive held pieces, means for rolling the pieces while stretched, and means for securing the pieces in their rolled condition.

54. In a machine of the character described, means to feed successive pieces of sheet material, means to hold said pieces, a circuit-traveling spring-closed gripper, cam-opened to grip and partially withdraw and temporarily stretch the successive held pieces, means for rolling the pieces while stretched, and means for securing the pieces in their rolled condition.

55. In a machine of the character described, means to feed successive pieces of sheet material, means to hold said pieces, a plurality of circuit-traveling spring-closed grippers, successively cam-opened to grip and partially withdraw and temporarily stretch the successive held pieces, means for rolling the pieces while stretched, and means for securing the pieces in their rolled condition.

56. In a machine of the character described, extended supporting means, rotary means, mechanism to sweep said rotary means along said supporting means, straddling elements on said rotary means, holding and stretching means coacting along said supporting means, and means to remove material from said straddling elements transversely of their path of travel along said supporting means, after the beginning of the sweep of said rotary means along said supporting means.

57. In a machine of the character described, a table, rotary means, mechanism to sweep said rotary means along said table and rotate said means, straddling elements on said rotary means, holding and stretching means coacting along said table, mechanism to withdraw the rotating means from said table, and a stripper traveling near said table, along the path of said rotary means, to strip material from said straddling elements on withdrawal of said rotary means from said table.

58. In a machine of the character described, first-creasing rolls, forming means, a second pair of rolls near the end of said forming means remote from the first-creasing rolls, a third pair of rolls farther on in this direction, with their axes at a substantial angle to the axes of the second pair of rolls, cutting means in receptive relation to said third pair of rolls, and mechanism in receptive relation to said cutting means for forming into packages the material severed by said cutting means.

59. In a machine of the character described, cutter-feeding means, a cutter-rotor, a blade on said rotor, a fixed blade with which said cutter-rotor blade coacts, a table beyond said fixed blade, having a transverse opening curving away from the table surface and out through the end of the table remote from said fixed blade, a folding-arm, a shaft journaled transversely of said table on which said arm is slidably lengthwise of

- the shaft and with which said arm swings along the curve of said opening, a folding-bar on said arm, extending toward said opening, a wrist-pin rotated with said rotor, 5 an operative connection between said shaft and said wrist-pin having inoperative relation to said wrist-pin during parts of the wrist-pin revolutions, at the table-surface and table-end limits of folding-arm swing, 10 respectively, mechanism sliding said arm toward said table at the surface limit and from said table at the end limit of said swing, said folding-bar being thus swung past the surface end of the curve of said 15 opening before the coaction of said blades, and swung past the other end of said curve in the interval, and mechanism in receptive relation to said other end of said curve for forming into a package the material operated upon by said blades and said folding-bar. 20
60. In a machine of the character described, a table, holding means near one end of said table, gripping means traveling past said holding means, mechanism causing said gripping means to open at said holding means and then close and travel along said table away from said holding means in closed condition, a feeder alongside said table, a chute leading to said feeder, a cutter between said chute and said feeder, mechanism operating said cutter and said feeder successively across said chute, means rotary on a transverse axis and having a pair of elements and a third element with a space between it and said pair, mechanism to slide said rotary means to a position where said space is in receptive position before said feeder and then slide said rotary means across said table with said pair of elements adjacent to the table surface, and adjacent to said holding means, mechanism for moving said rotary means from said holding means along said table, a pinion concentrically fixed on said rotary means, a slide- 25

- means across said table with said pair of elements adjacent to the table surface and adjacent to said holding means, mechanism for moving said rotary means from said holding means along said table, a pinion concentrically fixed on said rotary means, a 70 slideable rack meshing with said pinion, mechanism for sliding said rack simultaneously with and in direction opposed to said movement of said rotary means, and mechanism in receptive relation to the other end 75 of said table to complete a rolled package from material initially rolled by said rotary means in coaction with said gripping means. 62. In a machine of the character described, initial-rolling mechanism, a rolling-table in receptive relation to said mechanism, side preliminary-rolling belts adjacent to said mechanism, a middle preliminary-rolling belt adjacent to said mechanism and traveling partially over said rolling-table, side final-rolling belts traveling over said rolling-table, a cutting-roll and a moistening-roll juxtaposed on transverse axes past said middle belt, means for feeding tape between said rolls, means to supply moisture to said moistening-roll, means on said moistening-roll whereby said roll moistens the tape and means on said cutting-roll whereby said cutting-roll severs said tape within its moistened area, tape-guiding means between said rolls and said rolling-table, yieldable away from said middle belt, and a middle final-rolling belt past said tape-guiding means, traveling therefrom over said rolling table. 63. In a machine of the character described, initial-rolling mechanism, a rolling-table in receptive relation to said mechanism, means for feeding adhesive tape toward said table, preliminary-rolling belts traveling toward said feeding means, and final-rolling belts traveling beyond said feeding means. 64. In a machine of the character described, material-rolling means, means to apply tape to the rolling material, and a variable-speed operative connection between the means. 65. In a machine of the character described, means for initially rolling material, means to complete the rolling, and a variable-speed operative connection between the means. 66. In a machine of the character described, mechanism for initially rolling material, mechanism for completing a rolled package from the initially rolled material, and a variable-speed operative connection between said mechanisms. 67. In a machine of the character described, material-rolling mechanism, means to apply tape to the rolling material, and frictionally acting operative connecting mech-

anism for driving said rolling mechanism and said tape-applying means at various relative rates of operation.

68. In a machine of the character described, mechanism for initially rolling material, mechanism for completing a rolled package from the initially-rolled material, and a frictionally acting variable-speed operative connection between said mechanisms.

69. In a machine of the character described, mechanism for initially rolling material, mechanism for additionally rolling the material, mechanism for applying tape to the material, and variable-speed operative connections between the respective mechanisms.

70. In a machine of the character described, mechanism for initially rolling material, mechanism for additionally rolling the material, mechanism for applying tape to the material, and frictionally acting variable-speed operative connections between the respective mechanisms.

71. In a machine of the character described, transverse creasing rolls and transverse rolls to recrease or conserve the crease of material from said creasing rolls, forming means between the two sets of rolls, upright rolls beyond the second-mentioned rolls, transverse cutter-feeding rolls beyond these upright rolls, rotary cutting means beyond the cutter-feeding rolls, positive operative connections between the various rolls and the rotary cutting means, whereby all of said rolls and said means are driven synchronously, initial-rolling mechanism and mechanism to feed material from said cutting means to said initial-rolling mechanism, positive operative connections between said rolls and said cutting means and the latter mechanisms, operating these mechanisms in synchronism with said rolls and cutting means, mechanism to complete the rolling of the material, and mechanism to secure the material in its rolled condition, and variable-speed operative connections between these last two mechanisms, respectively, and the previously mentioned mechanisms.

72. In a machine of the character described, a rolling-table, a sheave transverse to said table near one end thereof, three sheaves transverse to said table thereover, side belts around the first sheave and the next sheave, a middle belt around the first sheave and the third sheave, side belts around this third sheave and the fourth sheave, another sheave intermediate of the third and fourth sheaves over said table, and a middle belt around this intermediate sheave and said fourth sheave, tape-applying means between the two middle belts and between the last mentioned side belts, and means for driving said belts.

73. In a machine of the character described,

a rolling-table, a sheave transverse to said table near one end thereof, three sheaves transverse to said table thereover, upwardly yieldable bearings for the respective sheaves, side belts around the first sheave and the next sheave, a middle belt around the first sheave and the third sheave, side belts around this third sheave and the fourth sheave, another sheave intermediate of the third and fourth sheaves, transverse over said table, a spring-pressed pivoted bearing for this intermediate sheave, and a middle belt around this intermediate sheave and said fourth sheave, tape-applying means between the two middle belts and between the last mentioned side belts, and means for driving said belts.

74. The process of wrapping consisting of applying an object to a wrapper together with elements astraddle of the wrapper edge in rotary motion, initially rolling the wrapper around the object, and then completing the rolling and securing the wrapper in its rolled condition.

75. The process of wrapping consisting of stretching a wrapper, applying an object to the wrapper with elements astraddle of the wrapper edge in rotary motion, initially rolling the wrapper around the object, and then completing the rolling and securing the wrapper in its rolled condition.

76. The process of wrapping consisting of feeding a wrapper web through intermittently-cutting means, severing a wrapper, applying an object to the wrapper together with elements astraddle of the wrapper edge in rotary motion, initially rolling the wrapper around the object, and then completing the rolling and securing the wrapper in its rolled condition.

77. The process of wrapping consisting of feeding a wrapper web through intermittently-cutting means, severing a wrapper, stretching the wrapper, applying an object to the wrapper together with elements astraddle of the wrapper edge in rotary motion, initially rolling the wrapper around the object, and then completing the rolling and securing the wrapper in its rolled condition.

78. The process of wrapping consisting of longitudinally folding a wrapper web, feeding the folded web through intermittently-cutting means, severing a folded wrapper, applying an object to the folded wrapper together with elements astraddle of the wrapper edge in rotary motion, initiating a rolling of the wrapper around the object, and then completing the rolling and securing the wrapper in its rolled condition.

79. The process of wrapping consisting of longitudinally folding a wrapper web, feeding the folded web through intermittently-cutting means, severing a folded wrapper,

stretching the folded and severed wrapper, applying an object to the stretched wrapper together with elements astraddle of the wrapper edge in rotary motion, initiating 5 a rolling of the wrapper around the object, and then completing the rolling and securing the wrapper in its rolled condition.

80. The process of wrapping consisting of longitudinally folding a wrapper web, feeding the folded web through intermittently-cutting means, severing a folded wrapper, folding the thus folded wrapper transversely, bringing its ends close together, applying an object to the wrapper together 10 with elements astraddle of the wrapper edge in rotary motion, near said ends, initiating a rolling of the wrapper around the object, and then completing the rolling and securing the wrapper in its rolled condition.

20 81. The process of wrapping consisting of longitudinally folding a wrapper web, feeding the folded web through intermittently-cutting means, severing a folded wrapper, folding the thus folded wrapper transversely, bringing its ends close together, holding said ends and stretching the wrapper from said ends, applying an object to the wrapper together with elements astraddle of the wrapper edge in rotary motion, 25 near said ends, initiating a rolling of the wrapper around the object, and then completing the rolling and securing the wrapper in its rolled condition.

82. The process of wrapping consisting of making parallel folds longitudinally of a wrapper, bringing its side parts in against its middle, folding the thus folded wrapper transversely, bringing its ends close together, rolling said ends around an object, 30 completing the rolling of the wrapper around said ends and said object, and securing the wrapper in its rolled condition.

83. The process of packaging sheet material consisting of applying elements astraddle of the sheet edge in rotary motion, initially rolling the sheet, and then completing the rolling and securing the sheet in its rolled condition.

84. The process of packaging sheet material consisting of stretching the sheet of material, applying elements astraddle of the edge of the stretched sheet in rotary motion, initially rolling the sheet, and then completing the rolling and securing the sheet in its rolled condition.

85. The process of packaging sheet material consisting of feeding the material in a web through intermittently-cutting means, severing a sheet of said material, applying 60 elements astraddle of the sheet edge in rotary motion, initially rolling the sheet, and then completing the rolling and securing the sheet in its rolled condition.

86. The process of packaging sheet material consisting of feeding the material in a

web through intermittently-cutting means, severing a sheet of said material, stretching the sheet, applying elements astraddle of the edge of the stretched sheet in rotary motion, initially rolling the sheet, and then 70 completing the rolling and securing the sheet in its rolled condition.

87. The process of packaging sheet material consisting of longitudinally folding a web of said material, feeding the folded web through intermittently-cutting means, severing a folded piece of said material, applying elements astraddle of the edge of said piece in rotary motion, initially rolling said piece, and then completing the rolling 75 and securing the piece in its rolled condition.

88. The process of packaging sheet material consisting of longitudinally folding a web of said material, feeding the folded web through intermittently-cutting means, 80 severing a folded piece of said material, stretching said piece, applying elements astraddle of the edge of said stretched piece in rotary motion, initially rolling said piece, and then completing the rolling and securing 85 the piece in its rolled condition.

89. The process of packaging sheet material consisting of longitudinally folding a web of said material, feeding the folded web through intermittently-cutting means, 90 severing a folded piece of said material, folding the thus folded piece transversely, bringing its ends close together, applying elements astraddle of the edge of said piece in rotary motion, near said ends, initiating 95 a rolling of said piece, and then completing the rolling and securing the piece in its 100 rolled condition.

90. The process of packaging sheet material consisting of longitudinally folding a web of said material, feeding the folded web through intermittently-cutting means, 105 severing a folded piece of said material, folding the thus folded piece transversely, bringing its ends close together, holding said 110 ends and stretching the piece from said ends, applying elements astraddle of the edge of said stretched piece in rotary motion, near said held ends, initiating a rolling of said piece, and then completing the 115 rolling and securing the piece in its rolled condition.

91. The process of packaging sheet material consisting of making parallel folds longitudinally of a sheet of the material, 120 bringing its side parts in against its middle, folding the thus folded sheet transversely, bringing its ends close together, initially rolling the brought-together ends, and then completing the rolling and securing the 125 sheet in rolled condition.

92. The process of packaging sheet material consisting of making three parallel longitudinal folds in a sheet of the material, folding its side parts together against 130

its middle to meet near the middle fold, then folding said sheet along the middle fold with said side parts together and with their edges inside the folded sheet, then folding 5 the thus folded sheet transversely with its ends close together, then rolling the brought-together ends initially, and completing the rolling of the sheet around said initially rolled ends and securing the sheet in its 10 rolled condition.

93. The process of packaging consisting of feeding and severing pieces of sheet material, feeding articles to said material, and then forming said material into plural-ply 15 wrappers about the respective articles fed thereto.

94. The process of packaging consisting of feeding and longitudinally folding a continuous web, severing successive portions 20 from said web, and forming the respective portions into reduced longitudinal dimension by a plurality of transverse bends or folds.

95. The process of packaging consisting 25 of simultaneously stretching and forming a plurality of transverse bends or folds in a piece of sheet material, and placing an article within some of said bends or folds during said stretching and forming operations.

30 96. The process of packaging consisting

of compacting a piece of sheet material around an article shorter than the transverse width of the piece, and contracting lateral parts of said material over the article ends.

97. In a machine of the character described, a pair of rolls on substantially parallel axes and making tangential coacting approach to each other, one of said rolls having a middle ridge and flanking ridges 40 therearound, and the other roll having surrounding grooves receiving the respective ridges, and one of said rolls being recessed adjacent to the middle ridge and groove, whereby said rolls are adapted to form parallel creases in sheet material passed between them, and whereby said recessing of the roll leaves empty spaces in which the sheet material may stretch transversely to form the 45 middle crease.

98. The process of packaging which consists in forming parallel creases in sheet material, one of which creases is between two other ones of said creases, and simultaneously permitting said material to stretch transversely adjacent to said one of said creases, folding said material along said creases, and then suitably reducing said material to a compact form.

MERVIN B. CANNON.
